(57) **CLAIM**

The ornamental design for a compaction machine transmitter assembly, as shown and described.

DESCRIPTION

FIG. 1 is a top front right isometric view of a compaction machine transmitter assembly showing my new design, the transmitter assembly consisting of a transmitter and a transmitter casing;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a top left isometric view of the transmitter of the transmitter portion of a compaction machine transmitter assembly showing my new design;

FIG. 9 is a left side elevation view thereof;

FIG. 10 is a right side elevation view thereof;

FIG. 11 is a rear elevation view thereof;

FIG. 12 is a front elevation view thereof;

FIG. 13 is a top plan view thereof;

FIG. 14 is a bottom plan view thereof;
FIG. 15 is a front right isometric view of the transmitter
casing portion of a compaction machine transmitter assembly
showing my new design;
FIG. 16 is a left side elevation view thereof;
FIG. 17 is a right side elevation view thereof;
FIG. 18 is a front elevation view thereof;

FIG. 19 is a rear elevation view thereof; and,
FIG. 20 is a top plan view thereof.
The broken lines represent environmental structure and form
no part of the claimed design.
